(57) **CLAIM**

The ornamental design for a fishing rod rack, as shown and described.

DESCRIPTION

FIG. 1 is a perspective view of a fishing rod rack showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged view of the encircled portion shown in FIG. 1. The dot-dash lines are for the purpose of illustrating the enlarged view and form no part of the claimed design. The broken lines represent the portions of the design that form no part of the claim.

1 Claim, 8 Drawing Sheets
